UNITED STATES PATENT OFFICE.

CARRODUS BASTOW, OF GRANTWOOD, NEW JERSEY, ASSIGNOR TO STANDARD CONVERTING COMPANY, OF BALTIMORE, MARYLAND, A FIRM.

DESIGN FOR A RUG.

44,465.

Specification for Design.

Patented Aug. 12, 1913.

Application filed June 19, 1913. Serial No. 774,681. Term of patent 14 years.

To all whom it may concern:

Be it known that I, CARRODUS BASTOW, a citizen of the United States, residing at Grantwood, in the county of Bergen and State of New Jersey, have invented a new, original, and ornamental Design for Rugs, of which the following is a specification, reference being had to the accompanying drawing, forming part thereof.

The figure is a plan view of a rug, showing my new design.

I claim:

The ornamental design for a rug, as shown.

CARRODUS BASTOW.

Witnesses:

SAMUEL H. JORY,
PATRICK J. CARNEY.
